(57) **CLAIM**

We claim the ornamental design for a television with rollable display, as shown and described.

DESCRIPTION

FIG. 1 is a perspective view of a television with rollable display showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective view thereof showing a state of the display rolled up.

The broken lines illustrate portions of the television with rollable display that form no part of the claimed design. The broken lines in FIG. 8 depict environmental subject matter and form no part of the claimed design.
